TRACER MECHANISM FOR DUPLICATING MACHINES

Einar K. Johansen, Chicago, Ill., assignor to
Clearing Machine Corporation, Chicago, Ill.,
a corporation of Illinois

Original application January 27, 1937, Serial No.
122,608. Divided and this application June 21,
1937, Serial No. 149,370

11 Claims. (Cl. 90—62)

This application is a division of my co-pending application number 122,608 filed January 27, 1937.

In the aforesaid application there is shown and described a duplicating machine in which the relative movements of a cutting tool and a work piece are controlled by a tracer moving over the surface of a model or pattern to produce the contour of the pattern upon the work, and is particularly adapted for use with metal working machines, such as milling machines, boring machines, planers and the like, and may be built within as a component part of the machine or as an attachment.

The present invention is concerned more particularly with the tracer in connection with the valve mechanism which controls the operation of the machine, and which valve mechanism is in turn controlled by the tracer, and one of the objects of the invention is to provide an improved tracer mechanism by which the control may be quickly and easily reversed to permit reproduction of patterns either in duplicate or in reverse as desired, and at the same time provide a tracer valve which is of practical and relatively simple construction and yet extremely accurate, sensitive and reliable in operation.

To the attainment of these ends and the accomplishment of other new and useful objects as will appear, the invention consists in the features of novelty in substantially the construction, combination and arrangement of the parts hereinafter more fully described and claimed and shown in the accompanying drawings illustrating this invention, and in which

Figure 1 is a general elevational view of a horizontal boring machine equipped with tracer controlled duplicating mechanism embodying the features of this invention.

Figure 2 is a plan view of the machine shown in Figure 1.

Figure 3 is a sectional view taken on line 3—3, Figure 2, on an enlarged scale, showing the mechanism for drivingly connecting the tool support and the tracer slide.

Figure 4 is a sectional view taken on line 4—4, Figure 3, on an enlarged scale, showing details of the micrometer adjusting mechanism comprising a part of the connecting mechanism of Figure 3.

Figure 5 is a sectional view taken on line 5—5, Figure 4.

Figure 6 is a longitudinal sectional view, on an enlarged scale, of the front portion of the tracer.

Figure 7 is a longitudinal sectional view of the rear portion of the tracer.

Figure 8 is a detail sectional view, on an enlarged scale of the tracer arm bearing support.

Figure 9 is a sectional view, on an enlarged scale, of a modified form of the tracer valve and valve control mechanism.

Figure 10 is a detail view partly in elevation and partly in section, on an enlarged scale, of a modified form of the tracer valve control means.

By way of illustration, the invention has been shown and will be described hereinafter as incorporated in a horizontal boring machine, but it is to be understood that this is not intended as a limitation of the invention to the particular machine described, it being contemplated that various changes and modifications may be made by those skilled in the art to adapt the invention to other types of metal working machines. It will also be understood that various changes in the form, construction and arrangement of the parts may be made without departing from the spirit and scope of the invention as expressed in the claims.

While a portion of the machine proper and of the mechanism which is controlled by the tracer and valve will be hereinafter described, it is to be understood that the present invention is directed particularly to the tracer mechanism and the valve control, the description of the machine being incorporated for the purpose of a clear understanding of the present invention.

Referring more particularly to Figure 1 of the drawings, the machine embodies a horizontally disposed bed 1 provided at one end with longitudinal guides or ways 2 on which the work support 3 travels. This work support comprises a saddle 4 in direct engagement with the ways 2 for movement along the bed 1 and is provided with horizontal transverse guides or ways 5 on which the work table 6 is mounted for movement transversely of the bed.

The work table 6 carries a vertically disposed angle plate 7 upon which a work piece 8 and a pattern or model 9 are mounted. Rigidly mounted at the other end of the bed 1 is an upstanding column 10 provided with vertical guides or ways 11 on which a spindle headstock 12 travels. The headstock includes a tool support 13 in the form of a horizontal spindle 13 projecting on the side adjacent the work support and carries a cutting tool 14 for operating on the work 8. The rear end of the spindle is operatively connected with a piston 15 operating in a cylin-

der 16 to which pressure fluid may be introduced selectively to move the spindle toward and from the work.

Suitable power drive means is provided for rotating the tool spindle 13, for feeding the headstock vertically in either direction, and for feeding the work table 6 transversely of the bed in either direction. In addition, a pump (not shown) driven by an electric motor 18 is arranged 10 to supply fluid under pressure to the cylinder 16 for feeding the tool spindle toward or from the work.

As shown in Figure 1, the pump together with the motor 18 and a suitable fluid reservoir or sump 15 is enclosed in a separate casing 20 adapted to be mounted at a convenient position adjacent the machine.

Upon the headstock 12 is rigidly mounted a bracket 21 having a horizontally disposed dove-tailed slideway 22 (Figures 2 and 3) in which a slide 23 supporting a tracer 24 is mounted for movement parallel to the axis of the spindle 13.

The tracer is of the type having a tracer arm 25 mounted for slight universal movement with reference to a head or casing 26 and having a tip 27 shaped substantially like the tool 14 and adapted to engage the surface of the pattern 9 as the tool operates on the work piece 8. Since the tracer head 26 is rigidly mounted on the headstock, the tracer tip and tool move together with the headstock and in fixed relation as to distance apart so that they describe a series of parallel paths relative to the work and pattern in the combined vertical movement of the headstock and the traversing movements of the work table.

With tracers of this type, movements of the tool 14 toward and from the work at right angles to the traversing path are controlled by valve mechanisms interposed in the hydraulic circuit of the cylinder 16 and adapted to be actuated by the independent movement of the tracer arm 25 incident to the tip 27 encountering either a rise or depression in the surface of the pattern.

Upon such movement of the tool, it is necessary to impart a proportionate movement to the tracer tending to restore the tracer arm to neutral position and maintain the tip 27 in constant, substantially uniform contact with the pattern.

The relative direction of the tracer movement is dependent upon whether the work is to be a duplicate of the model or a reverse copy of the same, in the first instance the tool and tracer moving to exactly the same extent or degree and in the same direction, while in the latter instance the tool and tracer are moved in opposite directions.

To co-ordinate the movements of the tool and tracer, the tracer slide is arranged to be driven directly from the tool spindle 13 by means of a positive geared driving connection interposed between the slide and spindle.

Referring particularly to Figures 2 and 3, the driving connection comprises, in the present instance, a vertical shaft 28 journaled in a vertical bearing 29 secured to the headstock 12. A pinion 29—A fast on the lower end of the shaft 28 is arranged to mesh with a rack 30 formed on a sleeve 31 adapted to reciprocate with the spindle 13. Thus the forward and backward movements of the spindle serve to rotate the shaft 28.

The shaft 28 is disengagably connected with a second shaft 32 in axial alignment with the first mentioned shaft through the medium of a sleeve 33 keyed to the lower shaft and having clutch teeth 34 engaging with complementary teeth on a sleeve 35 on the shaft 32. The sleeve 35 is operatively connected to the shaft 32 through the

medium of a micrometer adjusting mechanism 36 by which the angular relation of the shafts may be varied in infinitely small steps as will appear presently. The sleeve 33 is arranged for movement axially to the shaft 28 to engage or disengage the clutch teeth at will, the teeth being disengaged when the machine is to be operated without tracer control. A yieldable detent 37 (Figure 4) holds the sleeve in clutch engaging relation.

The upper end of the shaft 32 is journaled in a suitable bearing 38 supported in a gear box 39 on the rear end portion of the bracket 21. Fast on the upper end of the shaft 32 is a bevel gear 40 adapted to mesh with bevel gears 41 and 42 constituting a reversible clutch mechanism for driving a transverse shaft 43 journaled in anti-friction bearings 44 supported in the gear box 39. The gears 41 and 42 are formed integrally with or rigidly secured to a sleeve 45 splined to the shaft 43 for movement axially thereof. A pinion 46 fast on the shaft 43 is arranged to mesh with a rack 47 formed on a rod 48 extending rearwardly from the tracer slide 23. Thus the reciprocatory movements of the spindle 13 are communicated to the tracer slide through the shafts 28 and 32 and the gears 40 and 41 or 40 and 42. The movements of the spindle 13 and slide 23 are in the same direction when the gear 40 is meshed with the gear 42 and in opposite directions when the gear 40 is meshed with the gear 41. The gears 41 and 42 are shiftable preferably by means of a lever 49 (see Figure 2) pivoted on a bracket 50 formed on the gear box 39. One end of the lever 49 is formed with two legs to straddle the hub of the gear 41, each leg having a pin 51 engaging in an annular groove 52 formed in the hub of the gear. Thus the gears 41 and 42 may be shifted axially of the shaft 43 to cause one or the other to mesh with the driving gear 40 by rocking the lever 49 about its pivot. A spring 53 secured to a rearward extension of the lever is normally operative to hold the gears 41 and 42 in mesh. A solenoid 54 having its armature 54—A suitably secured to the other end of the lever 49 operates when energized to shift the gear assembly and mesh the gear 42 with the driving gear 40 for reverse operation of the machine. This reversing operation may also be effected manually when desired through the medium of a handle 55 constituting an extension of the lever 49.

Referring to Figures 4 and 5, the micrometer adjusting mechanism 36 comprises a worm wheel 59 keyed to the lower end of the shaft 32 and rigidly held in place thereon by a set screw 59—A disposed opposite the keyway. The worm wheel is enclosed in an annular housing 60 formed integral or rigidly secured to the sleeve 35. Meshing with the worm wheel 59 is a worm 61 fast on a transverse shaft 62 journaled in bearings 63 mounted on the housing 60. In the present instance the bearings 63 are threaded into the housing so that they may be conveniently adjusted to remove all end play with the shaft 62. The shaft 62 is provided at opposite ends with hand wheels 64 by which it may be rotated and, through the action of the worm 61 and worm wheel 59, thus rotate the sleeve 35 relative to the shaft 32. Since the sleeve 35 is drivingly connected with the shaft 28 through the clutch teeth 34, it will be apparent that this operation serves to rotate the shaft 32 relative to the shaft 28. This movement is communicated to the tracer slide in the usual way so that the relative position of the tracer tip 27 and the tool 14 may be varied accurately in infinitely small steps to accurately 75

position them in desired relationship to the pattern and the work. Accurate adjustment is facilitated by the provision of a graduated scale 65 on the hub of each of the hand wheels 64.

5 The micrometer adjustment above described may be utilized to advantage in initially setting up the machine as it makes it unnecessary to place the pattern in exactly the same plane as the work piece. After the work and pattern are 10 mounted on the support 7, the tool 14 may be advanced into contact with the work independently of the tracer by disengaging the clutch 34. The clutch is then engaged and the tracer tip advanced into contact with the pattern by 15 manipulating the hand wheel 64. When the tracer is to be moved through a considerable distance, this may be done conveniently and rapidly by disengaging the clutch 34 and rotating the entire micrometer mechanism.

20 The clutch 34 is then engaged and the tracer tip is backed away from the pattern by operating the hand wheel 64. The extent of this backward movement determines the depth of the cut taken by the tool 14 in the surface of the work 25 piece.

For precision work it is essential for the tracer to follow the movement of the tool exactly, as any lost motion between these parts will necessarily result in inaccurate reproduction. Means are 30 provided in the present instance for eliminating all possibility of such lost motion by effectually taking up the play and backlash in the gears, clutch and other parts of the spindle and slide connecting mechanism.

35 To this end the rod 48 by which the tracer slide 23 is driven, is provided at its rear end with a piston 66 operating in a closed cylinder 67 supported on a bracket 21. Provision is made for supplying pressure fluid to the rear end of the 40 cylinder through a duct 68 (see Figure 1) so that when the machine is in operation, the piston is continuously yieldably urged in a direction tending to move the slide 23 and tracer toward the pattern. With this arrangement all backlash in 45 the gears and clutch mechanism is taken up and the tracer and tool spindle are moved together in exactly the same degree either in the same or in opposite directions.

Referring now more particularly to Figures 6 50 and 7, the tracer 24 which constitutes the essential portion of the present invention, and which controls the forward and backward movements of the tool spindle and tracer slide, comprises an elongated hollow casing constructed in 55 the present instance in three sections 71, 72 and 73 rigidly secured together to form a unitary tracer head structure.

The section 71 disposed at the rear end of the assembly constitutes a housing for the tracer 60 valve and to this end is provided with a series of three ports 74, 75 and 76 arranged in a line extending longitudinally of the casing. A fourth port 77 is located at one side of the port 75 as 65 will be seen by reference to Figure 2 of the drawings.

Connecting with the port 77 is a duct 78 (see particularly Figures 1 and 7) leading from the discharge or pressure side of the source of supply of fluid pressure. Ducts 79 and 80 extend from 70 the ports 74 and 76, respectively, to a reversing valve (not shown) which valve in turn is connected with opposite ends of the spindle actuating cylinder 16 (not shown). A discharge duct or drain 83 extends from the port 77 (see Figure 1) 75 to the sump of the pump.

The casing section 71 is closed at one end by the section 72 and at the other end by an end plate 84, the several parts being rigidly secured together by bolts 85. As herein shown, the end plate 84 is provided with a depending arm 86 constituting a bracket for supporting the casing structure on the slide 23.

Enclosed within the casing 71 is a cylindrical sleeve 87 formed with accurately spaced internal circumferential grooves 88, 89 and 90 communicating with the ports 74, 75 and 76 through apertures 88—A, 89—A and 90—A extending through the sleeve. As herein shown, the sleeve 87 is constructed in three parts to facilitate manufacturing within the extremely close limits essential for 15 this type of mechanism. The sleeve is fitted tightly in the casing section 71 and held rigidly in place against an internal shoulder 91 on the casing wall by an annular member 92 carried on the end of the casing section 72 and disposed so 20 as to abut against the end of the sleeve. With this construction, accurately dimensioned openings for the ports 74, 75 and 76 are readily obtained with ordinary manufacturing processes.

Communication between the several ports in 25 the casing is controlled by a hollow, cylindrical valve member 93 slidably mounted for endwise movement in the sleeve 87. The valve member is formed with accurately spaced peripheral grooves 94, 95 and 96 adapted to co-operate with 30 the grooves 88, 89 and 90 in defining passages between the ports. The outermost or end grooves 94 and 96 are provided with apertures 97 communicating with the interior of the member and thus with the discharge port through the 35 medium of suitable channels 98 formed in the casing wall, as shown in Figure 2.

Preferably, the grooves in the member 93 are so positioned that, when the member is in intermediate or neutral position as shown in Figure 40 7, the openings for ports 74, 75 and 76 are tightly closed to prevent the flow of pressure fluid through the valve. When the valve member is moved to the right as viewed in the drawings the groove 95 connects the ports 75 and 74 so as to 45 direct pressure fluid from the duct 78 into the duct 79. At the same time, the port 76 is connected to the port 77 by way of the groove 96 and aperture 97. Movement of the valve member 93 in the other direction from neutral position connects the port 75 with the port 76 and likewise connects the port 74 with the port 77. Thus, by small movements of the valve member, the ducts 79 and 80 leading to the spindle actuating cylinder 16 may be connected selectively with 55 the pressure duct 78 or the drain duct 83.

Suitable means is provided for confining the movement of the valve member 93 within predetermined limits. As herein shown this means comprises an annular member 101 secured to the 60 end of the sleeve 87 adjacent the retaining member 92 by means of screws 102, the retaining member being slotted as at 103 to accommodate the heads of the screws. The member 101 is formed with an accurately dimensioned internal 65 peripheral notch 104 adapted to receive an annular member 105 rigidly secured to the valve member 93. The depth of the slot 104 is greater than the thickness of the member 105, the difference representing the range of movement of the 70 member in the slot and therefore the range of movement of the valve member.

When the machine is in operation movements of the valve member 93 are controlled by the tracer arm 25 through the medium of a valve 75

- actuating member 106 slidably mounted for endwise movement in the casing section 72. In the embodiment shown in Figure 7 of the drawings, a push rod 107 slidably supported in a gland 108 5 mounted in the end of the casing section 72 provides an operative connection between the valve member and the actuating member.

The push rod bears against a pad 109 on a transverse web 109—A rigid with the valve member, the pad being disposed substantially centrally of and co-axially in the member. A compression spring 110 interposed between the pad 109 and a collar 111 anchored to the push rod tends to urge the rod and valve member apart 15 for reasons that will appear presently.

Bearing against the opposite side of the pad 109 is a second push rod 112 slidably supported in a gland 113 mounted in the end plate 84. The rod 112 extends rearwardly through a tubular 20 extension 114 of the end plate 84 and through a hollow adjusting screw 115 threaded into the same. A compression spring 116 interposed between the end of the screw 115 and a collar 117 abutting against a shoulder on the push rod, 25 urges the rod to the left as viewed in Figure 7 and thus tends to shift the valve member to the left against the action of the spring 110. The spring 116 is of heavier construction than the spring 110 so that the pad 109 is normally held 30 in tight engagement with the push rod 107 and the latter is urged to the left against the actuating member 106. The pressure exerted by the spring 116 may be readily adjusted by turning the screw 115.

35 The impositive connection between the valve member 93 and the operating elements provided by the construction above described makes it unnecessary to align the push rod bearings exactly with the bore of the valve member, thus 40 materially simplifying the manufacture and assembly of the parts. The valve member is enabled to move freely without binding and consequently responds more quickly and accurately to slight movements of the actuating member 106 45 under the influence of the tracer arm 25. The valve actuating member 106 is preferably of hollow cylindrical construction and is provided at each end with a peripheral bearing surface 118 for sliding engagement with the walls of a 50 cylindrical hardened steel bearing member 119 mounted in the casing section 72.

As shown in Figure 6 the tracer arm 25 is 55 operatively connected to the abutting member 106 by means of a ball and socket joint comprising a ball member 120 rigidly mounted on the inner end of the tracer arm 25, and a socket 121 supported within and substantially centrally of the actuating member so that the assembled 60 parts occupy a minimum of space and yet provide a relatively long and firm bearing for the same. An annular retaining ring 122 threaded into the open end of the socket and locked in place by a suitable lock nut 123 maintains the ball 120 securely in the socket. The tracer arm 65 extends entirely through the tubular casing 73 which is threaded into the end of the section 72 and locked in place by a suitable lock nut 124 to provide a convenient means for adjusting the overall length of the casing structure. Mounted 70 intermediate the ends of the tracer arm adjacent the forward end of the section 73 is a bearing element 125 having a spherically formed bearing surface 126 adapted to co-act with an inclined bearing surface 127 formed within a hollow cylindrical stationary bearing element 128

threaded into the end of the casing section 73. The interior diameter of the element 128 is sufficiently greater than the diameter of the tracer arm and the element 125 so that the arm may be rocked about the pivot provided by the ball and socket joint when pressure is exerted laterally on the tracer tip 27. A nut 129 threaded on the bearing element prevents accidental movement of the element relative to the casing.

As shown in Figure 8 the relative positioning 10 of the bearing surfaces 126 and 127 is such that when the tracer arm 25 is rocked about its pivot, the bearing surface 126 rides upon the inclined surface 127 and shifts the tracer arm axially a distance determined by the degree of deflection 15 of the arm 25. The bearing 125 is normally centered in the bearing 128 by a compression spring 130 enclosed in a cap or guard 131 threaded on the tracer arm and bearing against the end of the element 128. The pressure exerted 20 by the spring on the tracer arm may be varied by rotating the cap 131 and determines the force required to rock the tracer arm out of normal or intermediate position.

It will thus be appreciated that the tracer arm 25 25 may be moved axially as well as laterally by reason of the tip 27 encountering a rise in the surface of the pattern. In either case, the valve actuating member 106 is moved endwise a proportionate amount and acts through the push 30 rod 107 to position the valve member 93. The relative positioning of the several parts is extremely important and these are preferably adjusted so that the valve member 93 may be shifted to its extreme forward operative position 35 by the spring 116 and push rod 112 when the bearing 126 is exactly centered in the bearing 127 and in engagement therewith. A slight rearward movement of the tracer arm produced by either axial or lateral pressure of the pattern 40 against the tip 27 serves to shift the valve member to neutral position. Further movement of the tracer arm shifts the valve member to its other operative position in which the hydraulic circuit connections are reversed. Adjustment 45 of the several parts is quickly and accurately effected by rotation of the casing section 73 relative to the section 72 and by rotation of the bearing element 128 relative to the casing section 73.

When the machine is in operation, the tip 27 50 is held in constant, substantially uniform contact with the surface of the pattern 9. The contact pressure is determined by the adjustment 55 of the springs 116 and 130. When the tip enters a depression in the pattern, the valve member 93 follows under the influence of the spring 116 and positions the valve ports so as to produce an appropriate movement of the tool 14. When the tip 27 encounters a rise in the surface of 60 the pattern the tracer arm is shifted rearwardly to vary the position of the valve member in the reverse direction.

The tool and tracer may be backed away from the work and pattern under manual control 65 when they are to be shifted to new traversing paths. To this end means are provided for moving the valve member 93 to its rearward position independently of the tracer arm. In the embodiment shown in Figure 7, this means comprises a solenoid 132 supported by a bracket 133 mounted on the end plate 86 of the casing and having its armature 134 operatively connected 70 with the projecting end of the push rod 112. When energized, the solenoid 132 draws the 75

push rod out of engagement with the pad 109 on the valve member, whereby the spring 110 is rendered effective to shift the valve member to the right.

5 Upon de-energization of the solenoid, the push rod 112 is shifted back into engagement with the pad 109 by the spring 116 and the valve member is returned to the position determined by the position of the tracer arm.

10 Figure 10 shows a modified valve control mechanism wherein the push rod is moved out of engagement with the valve member by manually operable means. In this construction, a nut 135 is threaded on the projecting end of the push

15 rod 112 and is locked by a second nut 136. The nut 135 constitutes a thrust bearing for engagement with the free end of a crank arm 137 carried by a shaft 138 rotatably supported on a bracket 139 on the end plate 84. A cam 140

20 fast on a shaft 141 also journaled in the bracket 139 is arranged to engage the crank arm 137 intermediate its ends. The cam is so shaped that when the shaft 141 is rotated, the crank arm 137 is rocked between a forward position

25 in which the push rod is disengaged from the arm, to a rearward position in which the push rod is shifted to the right sufficiently to permit the valve member 93 to move to its rearmost position under the influence of the spring 110.

30 For rotation of the shaft 141 a vertical shaft journaled at its upper end in a bearing 143 mounted on the bracket 139 carries a bevel gear 144 meshing with a bevel gear 145 fast on the shaft 141. Any suitable means such as a man-

35 ually operated lever (not shown) may be utilized to rotate the shaft 142. As herein shown, a spring 146 anchored at one end to a pin 147 projecting transverse from the shaft 141 and at the other end to a pin 148 threaded into the end plate 84 acts to normally maintain the low point of the cam 140 in engagement with the arm 137. Thus, the push rod 112 is normally free to move through its full stroke without interference. When the shaft 141 is rotated through a

40 quarter turn, the cam 140 operates through the arm 137 to shift the push rod and valve member 93 to neutral position. A further quarter turn of the shaft 141 shifts the valve member to its extreme rearward position.

45 50 A further modification of the tracer valve actuating mechanism is shown in Figure 10. In this embodiment the valve member is moved positively to its rearward position when it is desired to back the tool and tracer away from

55 the work and pattern. To this end, the push rod 112 is formed with a reduced inner end portion 149 adapted to extend through a slightly larger aperture 150 in the pad 109 and is loosely clamped thereto by a washer 151 abutting against

60 a shoulder on the rod and a nut 152 threaded on the end of the rod. The nut 152 is turned up sufficiently tight to take up substantially all end play between the rod and the valve member and yet permit lateral shifting of the parts 65 so that the push rod may readily center itself with respect to the valve member without causing the member to bind in the sleeve 87.

The push rod 107 is also modified in this instance by the provision of an enlarged hollow end portion 153 adapted to fit over the nut 152, thereby permitting the push rod to bear directly against the pad 109. No compression spring corresponding to the spring 110 is required in this construction.

75 Any suitable means may be supplied for with-

drawing the push rod 112 to its rearward position to shift the valve member 93. As herein shown, a solenoid 154 is provided for this purpose. The solenoid is mounted on a bracket 155 supported on the end plate 84 of the casing structure and its armature 156 is connected by a link 157 with the end of a lever 158 pivotally supported at 159 on the bracket 155.

The other end of the lever 158 is positioned for engagement with a sleeve 160 slidably supported 10 on the push rod 112 and yieldably connected therewith by a spring 161 interposed between the sleeve and a nut 162 threaded on the outer end of the rod.

The spring 161 is sufficiently stiff so that when 15 the lever 158 is rocked by energization of the solenoid 154, push rod 112 is shifted rearwardly against the action of the spring 116 until the valve member reaches its limit position. Further movement of the lever shifts the sleeve 160 axially of 20 the push rod against the action of the spring 161. With this construction, the solenoid armature 156 is enabled to make a full stroke without necessitating accurate adjustment of such stroke with reference to the stroke of the valve member. A 25 coiled spring 163 connection between the lever 158 and the bracket 155 withdraws the lever from engagement with the sleeve 160 upon deenergization of the solenoid and the push rod is returned to normal position by the spring 116. 30

The tracer solenoid 132 may be controlled in any suitable manner preferably from a switch or push button 164 arranged in a convenient position for the operator and this push button controls the circuit, the latter being supplied with 35 current from any suitable source. The parts of the machine (which do not constitute a portion of the present invention but which are described in detail in the aforesaid application) are so connected that the tracer solenoid 132 cannot be 40 energized when the machine is set for reverse operation and thus cause the tool to be fed towards the work.

To control the tracer by the solenoid 132 all that is necessary for the operator to do is to 45 actuate the push button or switch 164.

While the preferred forms of the invention have been herein shown and described, it is to be understood that various changes may be made in the details of construction and in the combination and arrangement of the several parts, within the scope of the claims, without departing from the spirit of this invention.

What is claimed as new is:

1. In a tracer mechanism, in combination, an 55 elongated hollow casing structure, a valve actuating member supported in one end of the casing for endwise movements relative to the casing, a tracer arm pivotally connected to said member and projecting through the other end of the casing, said arm having a tip adapted to engage the surface of a pattern, a bearing element having a spherically formed bearing surface carried by said arm adjacent said other end of the casing and adapted to co-operate with a second bearing 60 element supported on the casing, said second bearing element having a bearing surface disposed at an angle to the axis of the casing whereby lateral deflections of the tracer arm and tip are operative to produce an axial movement of 70 the arm and endwise movement of said valve actuating member, and yielding means tending normally to center said bearing elements one with respect to the other.

2. In a tracer mechanism, in combination, an 75

elongated hollow casing structure, a valve actuating member supported in one end of the casing for endwise movements relative to the casing, a tracer arm pivotally connected to said member and projecting through the other end of the casing, said arm having a tip adapted to engage the surface of a pattern, and means supporting said tracer arm intermediate its ends whereby lateral movements of the arm about its pivot are effective to impart endwise movement to said valve actuating member, said supporting means comprising a bearing element having a spherically formed surface fast on said arm, a second bearing element supported on the casing and having an inclined bearing surface on which said spherical bearing surface is adapted to slide in the lateral movement of said arm, and resilient means tending normally to center the first said bearing element with respect to the second said bearing element.

3. In a tracer mechanism, in combination, an elongated hollow casing structure, a valve actuating member supported in one end of the casing for endwise movements relative to the casing, a tracer arm pivotally connected to said member and projecting through the other end of the casing, said arm having a tip adapted to engage the surface of a pattern, and means supporting said tracer arm intermediate its ends whereby lateral movements of the arm about its pivot are effective to impart endwise movement to said valve actuating member, said supporting means comprising co-operating bearing elements on said arm and said casing, said elements having slidably engaging bearing surfaces disposed relative to each other so that lateral movement of one element relative to the other element is effective to impart an axial movement to said arm, resilient means tending normally to center said bearing elements, one with respect to the other, and means whereby the stress of said resilient means may be varied at will.

4. In a tracer mechanism, in combination, a casing structure, a tracer arm supported by said casing structure for universal movement, a valve actuating member adapted to be shifted axially of the casing in response to movements of said arm, a valve for controlling the flow of pressure fluid between inlet and outlet ports in said casing, said valve including a cylindrical valve member supported for movement axially of the casing, means yieldably urging said valve member toward one end of the casing, and means operatively connecting said valve member with said actuating member for movement thereby against the action of said yieldable means, said connecting means comprising a rod supported for endwise sliding movement in the casing and bearing at opposite ends against said actuating member and said valve member.

5. In a tracer mechanism, in combination, a casing structure, a tracer arm supported by said casing structure for universal movement, a valve actuating member adapted to be shifted axially of the casing in response to movements of said arm, a valve for controlling the flow of pressure fluid between inlet and outlet ports in said casing, said valve including a cylindrical valve member supported for movement axially of the casing, and having a pad rigidly supported co-axially therein, a rod slidably supported adjacent one end of the member with one end disposed so as to engage one side of said pad, spring means acting on said rod tending to shift said valve member toward one end of the casing, a second rod

slidably supported adjacent the other end of the member with one end engaging the other side of said pad and the other end engaging said valve actuating member to provide an operative connection between the valve member and the actuating member, and spring means interposed between said second rod and said pad operative to shift said valve member toward the other end of the casing when said first rod is drawn out of engagement with said pad.

6. In a tracer mechanism, in combination, a casing structure, a tracer arm supported by said casing structure for universal movement, a valve actuating member adapted to be shifted axially of the casing in response to movements of said arm, a valve for controlling the flow of pressure fluid between inlet and outlet ports in said casing, said valve including a cylindrical valve member supported for movement axially of the casing, means operatively connecting said actuating member and said valve member including means yieldably urging the valve member toward one end of the casing, a rod slidably supported at one end of the casing having one end positioned for engagement with said valve member, spring means acting on said rod to yieldably urge said valve member toward the other end of the casing against the action of said connecting means, and means including a solenoid for withdrawing said rod from engagement with said valve member to render the connecting means operative to move the valve member toward said one end of the casing.

7. In a tracer mechanism, in combination, a valve having a member movable from a neutral position to either of two operative positions, a tracer arm adapted to control the position of said member, and means for moving said member into one operative position independently of said tracer arm.

8. In a tracer mechanism, in combination, a valve having a member movable from a neutral position to either of two operative positions, a tracer arm adapted to control the position of said member, a solenoid adapted when energized to move said member into one operative position independently of said tracer arm, and circuit connections controlled from a remote point for energizing said solenoid.

9. In a tracer mechanism, in combination, a valve having a member movable from a neutral position to either of two operative positions, a tracer arm adapted to control the position of said member, and manually operable means for moving said valve member into one operative position independently of said tracer arm.

10. In a tracer mechanism, in combination, a casing structure, a tracer arm supported by said casing structure for universal movement, a valve actuating member adapted to be shifted axially of the casing in response to movements of said arm, a valve for controlling the flow of pressure fluid between inlet and outlet ports in said casing, said valve including a cylindrical valve member supported for movement axially of the casing, means operatively connecting said actuating member and said valve member including means yieldably urging the valve member toward one end of the casing, a rod slidably supported at one end of the casing having one end positioned for engagement with said valve member, spring means acting on said rod to yieldably urge said valve member toward the other end of the casing against the action of said connecting means, a crank arm operable to withdraw said rod from

engagement with said valve member to render the connecting means operative to move the valve member toward one end of the casing, and a cam for actuating said crank arm.

5 11. In a tracer mechanism, in combination, a valve having a member movable from a neutral position to either of two operative positions, a

tracer arm adapted to control the position of said member, and manually operable means for moving said valve member into one operative position independently of said tracer arm, the said means embodying a crank arm, a cam operable upon said crank arm, and means for actuating the cam.

EINAR K. JOHANSEN. 5
